UNITED STATES PATENT OFFICE.

EDWIN G. ROSE, OF WASHINGTON, DISTRICT OF COLUMBIA.

DESIGN FOR A GAME-BOARD.

SPECIFICATION forming part of Design No. 32,299, dated February 27, 1900.

Application filed January 29, 1900. Serial No. 3,237. Term of patent 31 years.

To all whom it may concern:

Be it known that I, EDWIN G. ROSE, a citizen of the United States, residing at Washington, District of Columbia, have invented and produced a new and original Design for a Game-Board, of which the following is a specification.

In the accompanying drawings, Figure 1 is a plan view of the board, and Fig. 2 is a vertical section taken laterally.

As shown, the leading feature is in the configuration of the surface of the board. The board is of approximately-rectangular shape

in outline and is provided with a central portion A, of the shape shown, having parallel sides and rounded ends and defined by a rib or raised part B. In each of the corners of the board is a depression, making the board symmetrical.

What I claim is—

The design for a game-board herein shown and described.

EDWIN G. ROSE.
